DESIGN FOR A VANITY MIRROR FOR AUTOMOBILES

Harry Golden, New York, N. Y.

Application April 25, 1947, Serial No. 138,611

Term of patent 7 years

(Cl. D14—6)

To all whom it may concern:

Be it known that I, Harry Golden, a citizen of the United States of America, residing at New York, in the county of New York and State of New York, have invented a new, original, and ornamental Design for Vanity Mirror for Automobiles, of which the following is a specification, reference being had to the accompanying drawing, forming part thereof:

Figure 1 is a front elevational view of an automobile vanity mirror embodying my new design;

Figure 2 is a top plan view thereof;

Figure 3 is a side elevational view thereof, and

Figure 4 is a rear elevational view of the same.

I claim:

The ornamental design for a vanity mirror for automobiles, as shown.

HARRY GOLDEN.
